DESIGN FOR A TOSSING TOY DEVICE

Charles Wahl, Jersey City, N. J.

Application July 27, 1937, Serial No. 70,681

Term of patent 3½ years

To all whom it may concern:

Be it known that I, Charles Wahl, a citizen of the United States and resident of Jersey City, in the county of Hudson and State of New Jersey, have invented a new, original, and ornamental Design for a Tossing Toy Device, of which the following is a specification, reference being had to the accompanying drawing, forming a part thereof.

Fig. 1 is a perspective view of a tossing toy device, showing my new design.

Fig. 2 is a side elevational view.

I claim:

The ornamental design for a tossing toy device, as shown.

CHARLES WAHL.
